UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WEFT-REPLENISHING MECHANISM FOR LOOMS.

Application filed April 17, 1922. Serial No. 553,341.

To all whom it may concern:

Be it known that I, EDWARD S. STIMPSON, a resident of Hopedale, in the county of Worcester and State of Massachusetts, have invented an Improvement in Weft-Replenishing Mechanism for Looms, of which the following is a specification.

The present improvement has reference to weft replenishing looms of the well known Northrop type wherein a rotary hopper or magazine carries a large number of bobbins which are transferred one by one into the running shuttle as the running weft becomes exhausted sufficiently to demand replenishment. So much of the Northrop loom as is necessary for an understanding of the present invention is illustrated in United States Letters Patent of Cobb & Adkins No. 648,898, May 1, 1900, and of Stimpson No. 664,790, December 25, 1900. As shown in each of these patents, a yielding bobbin head support is located in the path of the foremost bobbin in the hopper or magazine as said bobbin is transferred from the magazine into the shuttle, as indicated in Fig. 2 of said Patent No. 648,898. This yielding bobbin head support, as shown in said patents, is pivoted directly to the fixed stand secured to the breast beam of the loom upon which the magazine or hopper is rotatively mounted. The bobbin head support is subjected to a severe strain as the bobbin is being transferred, and this strain is transmitted to the stand upon which the bobbin head support is pivoted. This results in occasional breakage of a stand, thus necessitating the dismounting of the magazine and the substitution of an entirely new stand in order that the replenishing mechanism may continue to function.

The object of the present invention is to avoid this difficulty. In accordance with the present invention, the yielding bobbin head support is pivotally mounted upon an independent bracket which is detachably fastened to the magazine stand. Hence, if breakage occurs due to the shock of the bobbin transfer transmitted to the bobbin head support, only this bracket is broken and it can be replaced by a new one without removing the magazine or its stand from the loom. The pivot stud for the bobbin head support is fastened to this independent removable bracket by a headed pin, and

when the bracket is in place on the stand the head of the pin is located immediately beneath a portion of the stand so that it is impossible for it to jar loose. This bracket is fitted to the stand so that the stand withstands the strains imparted to the bracket thereby relieving the attaching devices from shock.

The present improvements are illustrated in the accompanying drawings, wherein—

Figure 1 is a view of the inner side of a portion of the magazine supporting stand showing the removable bracket and bobbin head support in place, the point of view from which these parts are seen being from the middle of the loom. Fig. 2 is a side view looking in the opposite direction from that in which Fig. 1 is seen. Fig. 3 is a view of the outer side of the removable bracket detached, looking at it in the opposite direction from that in which Fig. 1 is seen. Fig. 4 is an edge view of the bracket. Fig. 5 is a section in the plane indicated by the line 5—5 in Fig. 2.

The magazine stand A, is fixed to the breast beam of the loom in the usual way, and it has on its outer face (Fig. 2) the usual lateral ledge or guard B, which prevents premature radial displacement of the bobbins C, carried by the rotary magazine D. As shown in Fig. 2, the foremost bobbin which bears against the usual fixed stop E, on the stand A, is directly above the bobbin head support F. This bobbin head support F, turns on a fixed stud G, and is yieldingly maintained in its normal elevated position shown in Fig. 2 by a spring H, shown in Fig. 1. In all of these respects, the illustrated mechanism is substantially that shown in the aforesaid Patent No. 664,790.

In accordance with the present invention, this stud G, is not carried by the stand A, but it is secured to an independent bracket 10, by means of a headed pin 11, which extends centrally through the stud G, as shown in Figs. 2 and 5.

This bracket 10, is detachably but securely fixed to the stand A. The body of the bracket conforms in curvature to the curves of the stand. On its inner face (that is, toward the cloth) the stand has a recess 14 bounded at its top by a transverse shoulder 15 and at its bottom by an inclined shoulder 16. The bottom face of this recess has a transverse groove 13 open at its rear end.

The bracket is constructed so as to fit within this recess. As shown in Figs. 3 and 4, the bracket has at its outer side and near its lower end an inclined flange 18 furnishing an inclined face adapted to fit along side the inclined shoulder 16 of the stand. The upper transverse edge of the bracket has its face 17 adapted to fit inside the shoulder 15 of the stand. The bracket near its upper end has a transverse rib 12, on its outer face which fits within the groove 13 of the stand.

At its bottom the stand has a recess terminating at its front in a vertical shoulder 22 and at its rear in an inclined shoulder 32 (Figs. 1 and 2) substantially parallel with the inclined shoulder 16. At its extreme lower end the bracket has an elongated bearing 19 for the stud G, and this bearing projects outwardly beyond the flange 18 as indicated in Figs. 4 and 5, to constitute an outwardly extending lateral flange 20 which fits the bottom surface of the stand between the shoulders 22 and 32, as shown in Figs. 1, 2 and 5. The bearing 19, at its front has a flat vertical face 21 which seats against the vertical shoulder 22 on the stand. The rear face of the end 31 (Fig. 3) of the flange 20 is inclined and fits against the shoulder 32 of the stand.

The bracket is secured to the stand by bolts 24, and nuts 25, the bolts passing through holes 23 in the bracket. The interfitting parts of the bracket and stand serve to maintain the bracket definitely in place and to relieve the bolts 24, from any injurious strain or shock. The interfitting parts of the bracket and stand are disposed so as to transmit to the stand all up, down, forward and backward strains on the bracket due to the movement of the yielding bobbin head support. Downward movement of the bracket is prevented by the rib 12 fitting in groove 13 of the stand to which effect also the interfitting face of the flange 18 of the bracket and the shoulder 16 of the stand contribute. Upward movement of the bracket is prevented by the shoulder 15 and groove 13 of the stand and also by the bottom of the stand above the flange 20 of the bracket. Frontward movement of the bracket is prevented by the shoulders 16 and 22 of the stand. Rearward movement of the bracket is prevented by shoulder 32 of the stand. At the same time by simply removing the nuts 25, the bracket can be easily removed in case it becomes broken. This removal and the replacement of a new bracket can be effected without removing the stand or the magazine from the loom.

The flange 20 of the bracket is shaped at its margin 26 to constitute a continuation of the ledge or guard B, of the stand, as indicated in Fig. 2, thereby preventing any accidental radial displacement of the bob-

bins after they leave the guard B. As shown in Fig. 5, the head 27 of the pin 11 is at the upper surface of the flange 20 just beneath the part of the lower margin of the stand A, beneath which said flange 70 extends. When the bracket is fitted in place and secured to the magazine stand, the head of its pin is immediately beneath the stand A. Accordingly, it is impossible for the pin to jar loose or to be accidentally dis- 75 placed.

As shown in Fig. 5, the hub 28 of the bobbin head support F, is forked to fit the stud G, on both sides of the bearing 19 of the bracket. On the inner end of this hub 80 is the usual upwardly extending plate I, which carries the bolt J, around which the spring H, is coiled. This bolt extends loosely between two studs 29 projecting laterally from the inner face of the bracket, 85 a washer K, surrounding the bolt and bearing against the studs 29, serving as a bearing for the spring H. A hole 30, in the bracket accommodates the bolt J.

The shoulders 16 and 32 of the stand and 90 the corresponding interfitting faces 18 and 31 of the bracket are substantially perpendicular to the line of stress due to the spring H.

I claim—

1. A weft replenishing loom having, in combination, a fixed magazine-carrying stand; a bracket removably fastened to said stand, said bracket having a bearing at its lower end which fits beneath a portion of the stand; a pivot stud carried by said bearing; a headed pin extending through said bracket and the pivot stud, the head of the pin being located immediately beneath the stand when the bracket is secured thereto whereby the pin cannot become loose or detached; and a bobbin head support swinging on said stud.

2. A weft replenishing loom having, in combination, a fixed magazine carrying stand having a recess 14 provided with a transverse groove 13, a transverse shoulder 15, and an inclined shoulder 16, and said stand also having at its bottom a recess with a front vertical shoulder 22 and a rear inclined shoulder 32; a bracket removably fastened to said stand, said bracket having parts fitting into said recesses on the stand, and being provided with faces 17, 18, 21 and 31, interfitting respectively with said shoulders 15, 16, 22 and 32 on said stand, whereby said bracket is retained by said stand against up, down, frontward and backward movements; attaching means fastening the bracket to the stand; and a yielding bobbin head support on said bracket.

3. A weft replenishing loom having, in combination, a fixed magazine carrying stand; a fixed bracket removably fastened to

said stand; attaching means for fastening the bracket to the stand; and a yielding bobbin head support on said bracket, said bracket and stand having interfitting parts 5 including a transverse groove 13 on the stand and a transverse rib 12 on the bracket, said parts being disposed so as to transmit to the stand all up, down, frontward and backward strains on the bracket due to the movement of the yielding bobbin head 10 support, thereby relieving the attaching means from such strains.

In witness whereof, I have hereunto signed my name.

EDWARD S. STIMPSON.
